United States Patent Office

Des. 229,826

Patented Jan. 8, 1974

229,826

POURING SPOUT

George M. Raptis, 17866 Vicino Way,
Pacific Palisades, Calif. 90272

Filed Sept. 15, 1972, Ser. No. 289,295

Term of patent 14 years

Int. Cl. D9—07

U.S. Cl. D9—277

FIG. 1 is a perspective view of a pouring spout showing my new design;

FIG. 2 is a right end elevational view;

FIG. 3 is a left end elevational view;

FIG. 4 is a front elevational view; and

FIG. 5 is a bottom plan view.

I claim:

The ornamental design for a pouring spout, substantially as shown.
